UNITED STATES PATENT OFFICE

VAUGHN H. ROSS, OF VANCOUVER, BRITISH COLUMBIA, CANADA

SHINGLE-BUNDLE WIRE-BINDING DEVICE

Application filed December 27, 1926. Serial No. 157,133.

This invention relates to an improved method of securing together shingles in bundles for shipment. Its object is to expedite and improve the final operation in the manufacture of shingles, preparatory to shipment from the mill, in such a manner that they may be more suitable for transportation without liability to damage, and moreover to effect this improvement with a distinct saving both in time or labour over methods now 10 usually in vogue.

In carrying out my invention I prefer to utilize the wire tying machine as described in my patent application filed November 23, 1926, under Serial No. 150,345, which 15 lends itself with great facility to the operation detailed hereinafter.

In my invention I avoid using the flat metal band and the nailing of this to one 20 of the wood strips which act as cleats to the bundle, as is the usual practice, and instead place the bundled shingles in position for wire-tying by my machine (above referred to) and having first prepared the wood strips or cleats by securing both ends 25 from splitting by driving a fine wire nail transversely through them, at right angles to the direction of the binding wire and close to each end, I pass around the bundle and 30 over the cleats longitudinally a length of wire and thread the same through my machine, which tightens the wire to any required degree and ties the ends, leaving the bundle tightly bound, with the wire having 35 cut into the ends of the cleats, thus locking itself against any possible transverse movement such as may occur in transportation.

It is this locking of the wire within the 40 cleft produced by the tensional strain on the round wire (set up by my machine) and limited in amount by the resistance of the transverse nail, which is a salient feature of my invention, the details of which are fully 45 described in the specification following, ref-

erence being made to the accompanying drawings which form part of this application and in which:

Fig. 1 is a perspective view showing the application of my device to a bundle of shingles.

Fig. 2, an enlarged section of one end of the cleat.

The usual standard bundle of shingles is indicated by 5, the two wood strips or cleats 55 by 6, the round wire by 7. It is to be noted that when the ends of the binding wire are drawn together under strain preparatory to making the tie by twisting the ends together at 8, the tension causes the wire to cut into 60 the corners of the cleats as shown at 9 and more clearly by the enlarged section of the cleat end shown in Fig. 2.

This incipient cleavage of the cleats is however intercepted by the transverse wire 65 nail 10 which serves the double purpose of securing the grain of the wood against the splitting action and also of offering a resistance to any excessive cleavage which would otherwise occur.

Having now particularly described my invention, what I claim and desire the protection of Letters Patent is:—

1. A device for binding together a bundle of shingles and comprising a pair of longitudinal rectangular cross-sectioned wood cleats, said cleats being disposed across the centre and on opposite side of said bundle, a loop of round wire encircling said bundle and said cleats, said wire being on the approximate longitudinal centre line of said cleats and having its ends secured together under tensional strain, a short wire piercing said cleat near each outer corner, said short wire being transverse of said cleats and of 80 said longitudinal wire, and adapted to form a bearing for said wire.

2. A device for binding together a bundle of shingles and comprising, two longitudinal wood cleats of rectangular cross section, said 90

cleats being opposite each other and on opposite surfaces of the said bundle disposed transversely at about mid-position, each said cleat having a wire nail driven through it transversely near each outer corner and adapted to form a bearing for a tie wire loop, a loop of round wire encircling said bundle and said cleats and disposed lengthwise of said cleats, the ends of said wire being twisted together under tensional strain.

10 In witness whereof I affix my signature.
VAUGHN H. ROSS.
